UNITED STATES PATENT OFFICE.

SHEPARD W. CATELY, OF CORTLAND, NEW YORK.

CARRIAGE-SPRING.

SPECIFICATION forming part of Letters Patent No. 233,727, dated October 26, 1880.

Application filed September 1, 1880. (No model.)

To all whom it may concern:

Be it known that I, SHEPARD W. CATELY, a citizen of the United States, residing at the village of Cortland, in the county of Cortland and State of New York, have invented certain new and useful Improvements in Carriage-Springs; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

My invention relates to the construction of auxiliary carriage-springs wherein the recoil motion of the springs is regulated and controlled; and it consists in the employment of a spring composed of as many leaves as necessary to impart to it the strength and rigidity required for the use intended, and located immediately in the rear of the axle, as more fully hereinafter specified.

It is a well-known fact that all carriage-springs, as heretofore made, are stronger to resist the weight of a load bearing down than to withstand the momentum of the recoil from a sudden depression of the springs. My invention obviates this difficulty, moderating and governing the recoil movement, and thus preventing breakages of the springs and carrying the body of the vehicle more steadily over rough and uneven roads. These objects I attain by the mechanism illustrated in the accompanying drawings, in which—

Figure 1 represents a top-plan view of my improved invention; Fig. 2, an end view, and Fig. 3 a horizontal sectional view.

The letter A indicates the side springs, and B the connecting-spring, of an ordinary platform-spring.

C indicates the axle, and D and E are two spring-bars which support the body of the vehicle.

The letter F indicates an auxiliary semi-

elliptic spring, composed of as many leaves as may be necessary to impart to it the strength and rigidity required for the use intended. Said spring is located, as shown, immediately in rear of the axle C, and connected at its extremities to the side springs, A, by clips or fastenings a and at its central convex point to the spring-bar D. The leaves of the spring F are firmly secured together at or near the extremity of each crowning-leaf by means of metal clasps or bands b, thus strengthening and giving to the spring a rigidity nearly equal both in direct depression and recoil movement. The extremities of the spring F, when secured to the clips or clasps a, are drawn from their natural position when at rest, as shown by dotted lines x x, so as to create a constant tension in said spring, which is imparted to springs A B, slightly depressing the body of the vehicle toward the springs.

My invention is not limited in its application to platform-springs, but may be used with other styles, whether side or end springs, in each case having its connections adapted to the peculiar style and construction of the vehicle.

Having thus described my invention, what I desire to secure by Letters Patent is—

1. In platform-springs for vehicles, the auxiliary spring F, connected at its center with the body and at its ends with the axle and side springs, substantially as specified.

2. In combination with the side springs, the auxiliary spring F, the body of a vehicle, and clips a, so connected and arranged as to produce a constant downward tension upon the side springs and to resist the recoil movement of the vehicle-springs, as specified.

In testimony that I claim the foregoing as my own I have hereto affixed my signature in presence of two witnesses.

SHEPARD W. CATELY.
